UNITED STATES PATENT OFFICE

WINTHROP L. JACOBS, OF JERSEY CITY, NEW JERSEY, ASSIGNOR TO HARTFORD CARPET COMPANY, OF HARTFORD, CONNECTCUT.

DESIGN FOR CARPET.

Specification forming part of Design No. 11,399, dated September 9, 1879; application filed August 2, 1879.
[Term of patent 3½ years.]

To all whom it may concern:

Be it known that I, WINTHROP L. JACOBS, of Jersey City, in the county of Hudson and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

The design consists, essentially, of the irregular figures or rosettes A, B, C, D, E, and F, arranged upon the background. Between these figures are interspersed a series of smaller figures, squares, stars, hexagons, crown-shaped

and other figures of irregular form, as shown. The entire group of figures forms one rich mottled design, as shown in the photograph.

I claim—

1. The design for a carpet, consisting of the figures A B C and intermediate smaller figures, substantially as shown.
2. The design for a carpet, consisting of the figures D E F and intermediate smaller figures, substantially as shown.
3. The design for a carpet, consisting of the figures A B C D E F and intermediate smaller figures, substantially as shown.

WINTHROP L. JACOBS.
